William Newman, Middletown, Ohio, assignor to
The Gardner-Richardson Company, Middle-
town, Ohio, a corporation of Ohio

Application May 24, 1934, Serial No. 727,232

5 Claims. (Cl. 229—52)

This invention relates to a folding box of paper board construction.

The principal object of the invention is the provision of a folding paper board box formed of a blank providing side and end walls, the opposite sides of the box having cooperating end flaps one arranged on the outside and one on the inside of the box to form a box end, the inside and outside flaps being so constructed as to provide an integral handle which normally projects perpendicularly to the box end, the mentioned flaps also having interengaging portions adjacent the handle which hold the inside and outside flaps flat against one another and which hold the mentioned flaps against opening movements.

Another object of the invention is the provision of a folding box that can readily be arranged to form a closed container having a projecting handle at one end of the box so that the box can be readily carried, the handle being adapted to be folded flat on the box so as not to project beyond the width of the box end so that the same box can be used for delivery purposes.

Other objects and advantages of the invention will be apparent from the following description, the appended claims and the accompanying drawing, in which,—

Fig. 1 is a perspective view of a box embodying the present invention;

Fig. 2 is a view of the blank from which the box is formed;

Fig. 3 is a perspective view of one end of the box;

Fig. 4 is a view of the two cooperating end flaps of the box ready to be telescoped together;

Fig. 5 is a perspective view of the end of the box with the two end flaps interlocked together; and

Fig. 6 is a sectional view on the line 6—6 of Fig. 5.

Referring more particularly to the drawing by reference numerals, 10 designates a blank of paper board or similar somewhat flexible material, the blank being cut and scored so that one integral piece may be used to form the entire box. As shown, the blank 10 comprises opposite box sides 11 and 12 hinged together by an end-forming portion 13 which is integrally connected to the portions 11 and 12, the lines of bend being scored as indicated at 14. At opposite portions of these sides are end-forming portions or flaps 15 and 15', one flap 15 being shown turned in and lying flat against side 11. Extending parallel

to the portion 13 are the two cooperating end flaps 16 and 17.

The end-forming flaps 15 of the side 11 are interconnected with the end flap 16 to provide a corner as shown in Fig. 3. As herein shown this corner is provided by overturning a portion of the flap 16 and stapling it at 18 to the inturned edge portion of the flap 15, the latter being scored along the line 19 and having a corner portion 20 which can readily be tucked below the over-turned portion 21 of flap 16 as indicated at the right-hand corner of the box portion illustrated in Fig. 3. A similar connection between the flap 16 is provided at the opposite side of the side 11, and similar connections are also provided between the flaps 15' of side 12 and the end flap 17.

The flap 16 is cut to provide a hole 23 preferably rectangular in shape and of such size as to admit four fingers of a person. A cut 24, forming the end of the handle, is also provided at opposite sides of the handle-forming portion 25, each cut 24 extending inwardly from the free end of the flap, preferably transversely as shown. At each side of the handle-forming portion 25 is another cut 29 providing a slot that starts at a point spaced laterally from the end of the handle and preferably outwardly of the handle end, this cut extending out angularly away from the handle end as indicated in Fig. 2. The cut 29 preferably also has a portion 30 extending parallel to the handle.

The end flap 17 is adapted, when the box is closed, to lie on the outside of the box and overlie the flap 16. The flap 17 is provided with a handle-forming portion 32 formed by the cut 35 lines 33, 34. The sides of the handle portion correspond, in positioning, to the sides of the handle on cooperating flap 16, and the handle-forming portion 32 is also similar in construction to the portion 25 except that the material within the portion 32 is not removed. This leaves a tongue 37 which is adapted to extend under flap 16 when the box is closed. Adjacent the ends of the handle portion 32 the flap 17 is cut to provide outwardly extending edges 35, terminating 45 in hook portions 41 as shown in Figs. 2 and 4.

The blank is readily folded along the several scored lines indicated by the dash lines in Fig. 2, the portions 39 of flaps 15' being turned in to provide closed corners at the ends of side 13, as will be readily understood, and the two end flaps 11 and 12 brought opposite one another to the position indicated in Fig. 4. The enclosing portions of the box are then telescoped by closing one over the other, flap 16 being placed on the

inside, while the flap 17 overlies flap 16 as indicated in Fig. 5. The tongue 31 is placed beneath the free edge portion 40 of flap 16, the handle-forming portions 25 and 32 extending out perpendicularly to the box end as indicated. The hook-like corner portions 41 at opposite sides of the handle 32 are tucked into the two slots formed by the cuts 29, and serve to interlock with the end of the cut 29 so as to hold the two end flaps 16 and 17 against opening movement. The corner portions 41 and the cuts 29 adjacent opposite ends of the handle also serve to hold the flaps 16 and 17 one against the other, and the tongue 31 underlying the central portions of the flap 16 also serve to hold the two end flaps one against the other to provide a firm box closure and to resist bulging tendencies of the end flaps when the box is carried by the handle. It will be apparent that since the free end of flap 17 extends outwardly beyond the handle at opposite ends thereof and extends through the handle opening so as to underlie the flap 16 by reason of the tongue portion 31, the two flaps 16 and 17 are adequately held in close contact with one another in such a way as to effectively resist any bulging tendencies tending to separate these flaps when the box is supported by the handle and since the corner portions 41 are tucked into and hook around the cuts 29 on the inside flap, the box is held against opening.

The handle constituted by the handle-forming portions 25 and 32, which coincide in position when the box is closed, extends out perpendicularly at the center of the box end as shown in Fig. 1, when the box is to be carried by a person. However, the handle is so arranged that it can be readily folded upon itself so as to lie flat against the box end substantially within the confines of the lateral width dimensions of the box end in order that the same box can be used for delivery purposes. The handle-forming portions 25 and 32 are scored along the lines 43, which correspond in position on the two handle-forming portions, so that the outer end of the handle can be readily folded over and the inner portions of the handle can be folded to either side on the end flap 16 or 17. As the inner portions of the handles are scored along lines 44, and as the total projecting extent of the handle is approximately equal to the width of the box end, it will be understood that the handle can be folded flat against the box end and side to the position indicated in Fig. 6 so as not to project substantially beyond the side. It is held in this position by an adhesive strip 45 of paper or tape, which is applied over the end of the handle and to the box side 12 so that the entire package is of rectangular outline with no projecting portions that would interfere with convenient stacking of a number of such boxes in an effective manner.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

70 1. A folding paper box comprising opposite sides hinged together and having cooperating end flaps opposite their hinged connection, one end flap being arranged on the outside and one on the inside of the box to form a box end, said 75 inside and outside flaps each having an inte-

gral handle-forming portion extending perpendicularly to the box end with the two handle-forming portions coinciding when the box is closed, said inside end flaps having a slot adjacent each end of the handle starting at a point spaced outwardly of the handle end and extending out angularly away from the handle end, the outside end flap projecting beyond the handle ends and having hooked corner portions tucked into said slots so as to form an interlock holding the box closed.

2. A folding paper box comprising opposite sides hinged together and having cooperating end flaps opposite their hinged connection, one end flap being arranged on the outside and one on the inside of the box to form a box end, said inside and outside flaps each having an integral handle-forming portion extending perpendicularly to the box end with the two handle-forming portions coinciding when the box is closed, said inside end flap having a slot adjacent each end of the handle starting at a point spaced outwardly of the handle end and extending out angularly away from the handle end, the outside end flap having a tongue extending on the inside of said inside flap at the handle portion, said outside flap also projecting beyond the handle ends and having corners tucked into said slots and serving to hold the box closed.

3. A folding paper box comprising opposite sides hinged together and having cooperating end flaps opposite their hinged connection, one end flap being arranged on the outside and one on the inside of the box to form a box end, said inside and outside flaps each having an integral handle-forming portion extending perpendicularly to the box end with the two handle-forming portions coinciding when the box is closed, said inside end flap having a slot adjacent each end of the handle starting at a point spaced outwardly of the handle end and extending out angularly away from the handle end, said outside flap having a tongue extending on the inside of said inside flap beneath the handle, the outside flap also projecting beyond the handle ends outwardly of the handle and having corner portions tucked into and interlocked with said slots serving to hold the box closed.

4. A folding paper box comprising opposite sides hinged together and having cooperating end flaps opposite their hinged connection, one end flap being arranged on the outside and one on the inside of the box to form a box end, said inside and outside flaps each having an integral handle portion extending perpendicularly to the box end at the center thereof with the two handle-forming portions coinciding when the box is closed, said inside end flap having a slot adjacent each end of the handle, the outside end flap projecting beyond the handle ends outwardly thereof and tucked into said slots so as to hold the box closed, said handle portions being scored parallel to the box end at a distance from the box end substantially equal to half the box width so that the handle can be folded flat upon the box. 65

5. A folding paper box comprising opposite sides hinged together and having cooperating end flaps opposite their hinged connection, one end flap being arranged on the outside and one on the inside of the box to form a box end, said inside and outside flaps each having an integral handle portion extending perpendicularly to the box end at the center thereof with the two handle-forming portions coinciding when the box is closed, said inside end flap having a slot ad- 75

acent each end of the handle starting at a point outwardly of the handle end and extending out away from the handle end, the outside end flap projecting beyond the handle ends outwardly thereof and tucked into said slots so as to hold the box closed, the projecting length of the handle substantially corresponding to the distance

across the box end, said handle portions being scored parallel to the box end at a distance from the box end substantially corresponding to half the box width so that the handle can be folded flat upon the box within the width of the box end. 5
